ALKYLATION OF AROMATIC HYDROCARBONS

Louis Schmerling and Vladimir N. Ipatieff, Chicago, Ill., assignors to Universal Oil Products Company, Chicago, Ill., a corporation of Delaware

No Drawing. Application June 16, 1941,
Serial No. 398,233

6 Claims. (Cl. 260—671)

This invention relates to the production of alkyl aromatic compounds and more particularly to the production of alkylated aromatic hydrocarbons from aromatic hydrocarbons and naphthenic hydrocarbons.

Various methods have been proposed for the alkylation of aromatic hydrocarbons. These prior processes have mainly involved reacting aromatic and olefinic hydrocarbons. However, it has also been proposed to alkylate aromatic hydrocarbons with naphthenic hydrocarbons at low temperatures of up to about 120° C. in the presence of aluminum chloride or zirconium chloride. A disadvantage of these processes catalyzed by a metal halide is that the consumption of catalyst is relatively high and may be prohibitive from a commercial point of view when the fact is taken into consideration that spent catalyst of this type is generally not readily recovered.

In one specific embodiment the present invention comprises the manufacture of alkyl derivatives of aromatic hydrocarbons by treating aromatic hydrocarbons with naphthenic hydrocarbons in the presence of a zinc chloride-containing catalyst at a temperature of from about 200° to about 450° C.

The alkyl aromatic hydrocarbons thus formed may be used for increasing the antiknock value of gasoline motor fuels by blending, or they may be utilized in the preparation of pure alkylated aromatic hydrocarbons.

Aromatic hydrocarbons which are alkylated according to the process of this invention include benzene, toluene, other partially alkylated benzenes, naphthalene, partially alkylated naphthalenes, other poly-nuclear aromatic hydrocarbons, etc., which are obtainable by the distillation of coal, by the dehydrogenation of naphthenes, or by the dehydrogenation and cyclization of aliphatic hydrocarbons or of alkylated aromatic hydrocarbons.

Naphthenic hydrocarbons which are reacted with aromatic hydrocarbons according to the process of this invention include cycloparaffins and alkyl cycloparaffins with 5- and 6-carbon atom rings, particularly cyclopentane, cyclohexane, and a number of the corresponding alkylated cyclopentanes and alkylated cyclohexanes. The different alkylating naphthenic hydrocarbons which are thus utilizable will not necessarily be employed under the same conditions of operation within the limits hereinafter set forth.

The preferred catalyst for use in effecting the

process of the present invention is a composite of zinc chloride and a carrier, preferably alumina or a material containing a substantial proportion of alumina as clays, silica-alumina composites, bauxite, etc. Diatomaceous earth and silica are also utilizable as supporting material for zinc chloride.

The proportions of carrier and zinc chloride may be varied as desired to make catalyst composites of different activities. Thus it has been found possible and practical to make stable granular catalysts resistant to disintegrating influences by using from about 5 to about 50% by weight of zinc chloride and from about 95 to about 50% by weight of activated alumina or an alumina-containing carrier. These materials in finely powdered form, after thorough mechanical mixing, may be subjected to drying, pelleting, and heating operations to produce formed particles of catalyst suitable for use as alkylation reactor filling material. A suitable carrier may also be impregnated with an aqueous solution of zinc chloride, dried, and calcined to form a zinc chloride-carrier composite suitable for use in the process of the present invention.

Alkylations of the type hereinabove set forth may also be effected in the presence of hydrogen and/or of hydrogen chloride. There is little or no carbon formation upon the catalyst when alkylations are carried out under hydrogen pressure but carbon formation does occur to a substantial extent in the absence of hydrogen. Hydrogen chloride introduced to the reaction mixture appears to exert a promoting effect upon the zinc chloride-containing catalyst.

In effecting reaction between aromatic and naphthenic hydrocarbons according to the process of the present invention, the exact method of procedure will vary with the nature of the reacting constituents, their relative proportions, the activity of the catalyst employed, and other factors. A simple procedure utilizable in the case of an aromatic hydrocarbon which is normally liquid under the operating conditions consists in contacting said aromatic hydrocarbon with a naphthenic hydrocarbon or naphthenic hydrogen fraction in the presence of a zinc chloride-containing catalyst at a temperature of from about 200° to about 450° C. under a pressure of from substantially atmospheric to approximately 200 atmospheres. Intimate contact of the reacting components with the catalyst is effected by passing the reaction mixture through a fixed bed of the granular catalyst containing zinc chloride or the reacting components may be

mixed with finely divided catalyst and the resultant mixture or slurry may then be passed through suitable reactors such as heated tubular members. The hydrocarbon mixture subjected to alkylation treatment preferably contains a molar excess of aromatic hydrocarbon relative to naphthenic hydrocarbon in order to effect the production of a relatively high yield of alkylated aromatic hydrocarbons.

While methods of passing the aromatic and naphthenic hydrocarbons, either together or countercurrently, through a suitable reactor containing the granular catalyst are customary procedure, the condensation or alkylation reaction may be effected in a closed vessel in which some of the reacting constituents and products are in liquid phase and in which the catalyst is preferably in finely divided form and is maintained in dispersion or suspension by some method of agitation. The choice of operating procedure is dependent upon the circumstances such as temperature and pressure found to be most effective for producing the desired reaction between particular aromatic and naphthenic hydrocarbons.

Reactions between aromatic and naphthenic hydrocarbons in the presence of supported zinc chloride apparently involve the breaking of the cycloparaffin ring with the formation of alkyl radicals or fragments which undergo further reaction with the aromatic hydrocarbons or aromatic hydrocarbons present to form the alkylated and more-highly aromatic hydrocarbons. Thus benzene and cyclohexane interact to form toluene, ethyl benzene, xylenes, and higher boiling alkylated benzenes. Poly-alkylated aromatic hydrocarbons are formed when a mono-alkylated aromatic hydrocarbon originally charged undergoes further reaction with a naphthenic hydrocarbon or fragment formed by decomposition of a naphthenic hydrocarbon. Since the reactions of an aromatic hydrocarbon with a naphthenic hydrocarbon in the presence of a zinc chloride-containing catalyst are not understood clearly or completely, the above mechanistic concept should not be misconstrued to limit the generally broad scope of the invention.

The process thus utilizes cycloparaffinic hydrocarbons to combine with and alkylate aromatic hydrocarbons. The practical utility of the process appears in that various naphthenic hydrocarbons and hydrocarbon mixtures containing naphthenes may be employed as alkylating agents instead of the more reactive olefinic hydrocarbons. For example, instead of utilizing only the olefins present in cracked hydrocarbon mixtures and alkylating aromatic hydrocarbons (the olefins normally constituting only minor percentages of such cracked products), naturally occurring naphthenic hydrocarbons or naphthenic hydrocarbon fractions may be used which contain no olefins. In the case of hydrocarbon products containing olefins which may be derived by cracking naphthenes, the olefins may be removed by absorption in acid, by polymerization, or by more generally known alkylation reactions, and the residual hydrocarbons may then be employed to alkylate further amounts of aromatic hydrocarbons in the presence of a zinc chloride-containing catalyst by methods hereinabove indicated.

A composite of zinc chloride on a carrier is a preferred catalyst for the present process as it permits continuous alkylation of aromatics with naphthenes in the presence of a fixed catalyst bed. A zinc chloride-carrier composite also has the advantage over aluminum chloride utilized

for the same purpose, but under other operating conditions, in that the zinc chloride contained in the composite does not form addition compounds or complexes with aromatic hydrocarbons. Thus 5 while aluminum chloride forms sludge-like material, commonly referred to as lower-layer compounds, a zinc chloride catalyst remains relatively clean and active for a relatively long period of time particularly when charging hydrogen and hydrogen chloride simultaneously with the hydrocarbons undergoing conversion.

In general the products formed by interaction of a naphthenic hydrocarbon with a molal excess of an aromatic hydrocarbon are separated from the unreacted aromatic hydrocarbon by suitable means as by distillation, and the unreacted portion of the aromatic hydrocarbon originally charged is returned to the process and mixed with additional quantities of the naphthenic and 10 aromatic hydrocarbons being charged to contact with the zinc chloride-containing catalyst. The total alkylated product thus freed from the excess of the originally charged aromatic hydrocarbon is separated into desired fractions by distillation at ordinary or reduced pressure or by other suitable means.

The catalyst compositions hereinabove indicated are shown in terms of the proportions of the materials from which the catalyst composites 15 are generally prepared rather than the exact proportions of the catalyst composites themselves as these may be somewhat different due to formation of some zinc hydroxychloride, zinc oxychloride, or other material resulting from hydrolysis 20 or partial hydrolysis of a portion of zinc chloride or to other conversions which are not clearly understood.

The following example is given to illustrate the character of results obtained by the use of 25 the present process, although the data presented are only from a selected case and are not introduced with the intention of unduly restricting the generally broad scope of the invention.

80 parts by weight of benzene, 52 parts by 30 weight of cyclo-hexane, 2 parts by weight of hydrogen chloride, and 15 parts by weight of a composite formed from 25% by weight of zinc chloride and 75% by weight of alumina, were charged to a rotating autoclave, hydrogen was 35 introduced thereto to 100 atmospheres initial pressure, and the autoclave so charged was heated 4 hours at 400° C. under a maximum pressure of 267 atmospheres. After the autoclave had cooled, the reaction products removed therefrom 40 consisted of 113 parts by weight of liquid hydrocarbons, 16 parts by weight of gray-colored catalyst, and 6 parts by weight of a gaseous hydrocarbon fraction containing 21.4% by volume of propane, 32.6% isobutane, 15.4% normal butane, 45 and 30.6% of pentane and higher hydrocarbons. Fractional distillation of the 113 parts by weight of liquid hydrocarbons separated this material into 27% by volume boiling below 78° C., 55% 50 boiling between 78 and 86° C., 7% boiling between 85 and 105° C., 3% between 105 and 125° C., 4% between 125 and 160° C., and 4% of distillation residue. The different fractions boiling 55 above the recovered benzene contained substantial amounts of toluene, xylenes, ethyl benzene, and higher boiling alkylated benzenes.

The novelty and utility of the process of the present invention are evident from the preceding specification and examples given, although neither section is intended to unduly limit its 60 generally broad scope.

We claim as our invention:

1. A process for producing substantial yields of alkylated aromatic hydrocarbons which comprises contacting an aromatic hydrocarbon with a naphthenic hydrocarbon at a temperature of from about 200° to about 450° C. in the presence of a catalyst comprising zinc chloride, zinc oxychloride and zinc hydroxychloride.
2. A process for producing substantial yields of alkylated aromatic hydrocarbons which comprises contacting an aromatic hydrocarbon with a naphthenic hydrocarbon and hydrogen at a temperature of from about 200° to about 450° C. under a pressure of from substantially atmospheric to approximately 200 atmospheres in the presence of a catalyst comprising zinc chloride, zinc oxychloride and zinc hydroxychloride.
3. A process for producing substantial yields of alkylated aromatic hydrocarbons which comprises contacting an aromatic hydrocarbon with a naphthenic hydrocarbon at a temperature of from about 200° to about 450° C. under a pressure of from substantially atmospheric to approximately 200 atmospheres in the presence of hydrogen chloride and of a catalyst comprising zinc chloride, zinc oxychloride and zinc hydroxychloride.
4. A process for producing substantial yields of alkylated aromatic hydrocarbons which comprises contacting an aromatic hydrocarbon with a naphthenic hydrocarbon at a temperature of from about 200° to about 450° C. in the presence of a catalyst comprising zinc chloride, zinc oxychloride and zinc hydroxychloride.
5. A process for producing substantial yields of alkylated aromatic hydrocarbons which comprises contacting an aromatic hydrocarbon with a naphthenic hydrocarbon at a temperature of from about 200° to about 450° C. in the presence of a catalyst comprising zinc chloride, zinc oxychloride and zinc hydroxychloride.
6. A process for producing substantial yields of alkylated benzenes which comprises contacting benzene with a naphthenic hydrocarbon at a temperature of from about 200° to about 450° C. under a pressure of from substantially atmospheric to approximately 200 atmospheres in the presence of a catalyst comprising zinc chloride, zinc oxychloride and zinc hydroxychloride.
